UNITED STATES PATENT OFFICE.

ERNEST WILLOUGHBY PETTER, OF YEOVIL, ENGLAND.

MEANS FOR CONTROLLING THE SUPPLY OF LIQUID FUEL IN INTERNAL-COMBUSTION ENGINES.

1,249,478.

Specification of Letters Patent. Patented Dec. 11, 1917.

Application filed March 21, 1917. Serial No. 156,484.

To all whom it may concern:

Be it known that I, ERNEST WILLOUGHBY PETTER, a subject of the King of Great Britain and Ireland, of Nautilus Works, Yeovil, in the county of Somerset, England, have invented certain new and useful Improvements in Means for Controlling the Supply of Liquid Fuel in Internal-Combustion Engines, of which the following is a specification.

This invention relates to variable delivery fuel pumps for internal combustion engines and provides means for adjusting the moment of injection of the fuel when the engine is working or at rest so as to make the injection of the fuel earlier or later as required to suit the working conditions of the engine.

Apparatus made in accordance with this invention comprises a rotating shaft, a fuel feeding pump, transmission mechanism for operating said pump from said shaft comprising two eccentrics carried on said shaft one mounted upon the other, said eccentrics being relatively shiftable to move the center of the outer eccentric from its position of maximum throw to a position substantially coinciding with the center of the shaft, and by means for shifting the inner eccentric in relation to the shaft when the engine is working or at rest for the purpose of adjusting the moment of injection of the fuel.

Figure 1 is a perspective view showing hand operated means for altering the moment when the fuel is injected.

Fig. 2 is an elevation looking in the direction of the arrow in Fig. 3 with eccentric strap removed showing centrifugal means for altering the throw of the pump;

Fig. 3 is a section;

Fig. 4 is an elevation looking in the direction of the arrow Fig. 5, and

Fig. 5 is a section showing the means of adjusting the position of the inner eccentric in relation to the casing and shaft.

Upon the shaft *a* is fitted a carrier comprising a pulley *b* having a sleeve *c*, the carrier being provided with slots *d* *d*. On the sleeve *c* is disposed a casing *e* adapted to be adjusted angularly on the carrier by the pins 20 and 21 referred to later which pass through the slots *d* *d*. Upon the casing *e* is formed an eccentric *g* which bears 55 on the shaft *a*. On this eccentric is dis-

posed the outer eccentric *h*. The eccentric *h* is provided with lugs *j* *j*. On the casing *e* are mounted weights *k* *k* on the lugs *j* *j*. The weights *k* *k* are held toward the shaft *a* by means of springs *o* *o* which are attached to the casing at *p* *p* and to the weights at *q*. Upon the eccentric *h* is disposed the strap *r* to which the pump connecting rod *s* is attached.

In order to alter the moment when the fuel is injected the inner eccentric *g* has to be moved in relation to the carrier *b* *c* which is keyed to the shaft *a*. For this purpose a flange 2 provided with slots 3 and 4 is keyed to the shaft *a*, and a flange 5 is adapted to be slid on the shaft *a* by means of feathers 6 and 7 working in corresponding keyways in the said shaft. The feathers 6 and 7 are connected to a plate 8 and are adapted to be moved endwise by a screwed shaft 9 working in a fixed nut 10, the plate 8 being free to move on the shaft 9 between two collars 11 and 12 fixed to the shaft 9. 13 is a handwheel on the end of the screwed shaft 9. On the flange 5 are mounted two coarse-threaded screws 14 and 15 which are free to rotate in bearings in the said flange 2. These screws 14 and 15 engage two threaded holes in the flange 5. Upon the stems of the screws 14 and 15 are mounted cranks 16 and 17 which are connected by links 18 and 19 to pins 20 and 21 mounted on casing *e*. The pins 20 and 21 pass through the slots 3 and 4 on the flange 2. Alternatively the flange 5 can be made 90 to slide by means of a yoke ring and fork mounted on the circumference of the flange according to the well known manner employed in governors, friction clutches, and similar mechanisms.

In operation as the speed increases, the weights *k* *k* fly out and pull the eccentric *h* around the eccentric on the shaft *a* whereby the eccentricity is reduced, and consequently the throw of the pump and the amount of fuel supplied to the combustion chamber. When it is desired to alter the moment when the fuel is injected, the casing *e* and with it the inner eccentric *g* is moved in relation to the carrier *b* *c* by means of the handle 13 through the feathers 6 and 7, flange 5, screws 14 and 15, cranks 16 and 17, links 18 and 19, and pins 20 and 21 connected to the casing *e*.

The eccentric mechanism shown particu- 110

2
larly in Figs. 3 and 4 hereof is claimed in my application Serial No. 95,032, filed May 3, 1916.

What I claim and desire to secure by Letters Patent is:—

- 5 1. In a variable delivery fuel pump for internal combustion engines, in combination, a rotating shaft, a fuel feeding pump, transmission mechanism for operating said pump
- 10 from said shaft comprising two eccentrics carried on said shaft, one mounted upon the other, said eccentrics being relatively shift-able to move the center of the outer eccentric (in an approximately radial line toward the center of the shaft) from its position of maximum throw to a position substantially coinciding with the center of the shaft, a governor controlled by the speed of said shaft for shifting said eccentrics relatively so as to vary the operation of said pump in feeding said fuel, a member on said rotat-
ing shaft which is adapted to be rotated with said shaft and to be slid thereon, means for sliding said member when the shaft is either rotating or at rest, and means for utilizing said sliding motion to move the said inner eccentric angularly on the shaft to advance or retard the time of the stroke of the fuel injection pump.
- 15 20 25 2. In a variable delivery fuel pump for internal combustion engines, in combination, a rotating shaft, a fuel feeding pump, transmission mechanism for operating said pump

from said shaft comprising two eccentrics carried on said shaft, one mounted upon the other, said eccentrics being relatively shift-able to move the center of the outer eccentric (in an approximately radial line toward the center of the shaft) from its position of maximum throw to a position substantially coinciding with the center of the shaft, a governor controlled by the speed of said shaft for shifting said eccentrics relatively so as to vary the operation of said pump in feeding said fuel, a member on said rotat-
ing shaft which is adapted to be rotated with said shaft and to be slid thereon, means for sliding said member when the shaft is either rotating or at rest, and means for utilizing said sliding motion to move the said inner eccentric angularly on the shaft to advance or retard the time of the stroke of the fuel injection pump.

In witness whereof I have hereunto signed my name in the presence of two subscribing witnesses.

ERNEST WILLOUGHBY PETTER.
